Primary Examiner — Mitchell I. Siegel*Assistant Examiner* — Jasmine L. Comedy(74) *Attorney, Agent, or Firm* — Buchanan Ingersoll & Rooney PC(57) **CLAIM**

The ornamental design for a rear taillight for motor vehicle as shown and described.

DESCRIPTION

FIG. 1 is a perspective view of rear taillight for motor vehicle according to a first embodiment showing my new design;

FIG. 2 is a front view thereof;

FIG. 3 is a rear view thereof;

FIG. 4 is a right view thereof;

FIG. 5 is a left view thereof;

FIG. 6 is a top view thereof; and

FIG. 7 is a bottom view thereof.

FIG. 8 is a perspective view of rear taillight for motor vehicle according to a second embodiment showing my new design;

FIG. 9 is a rear view thereof;

FIG. 10 is a front view thereof;

FIG. 11 is a right view thereof;

FIG. 12 is a left view thereof;

FIG. 13 is a top view thereof; and,

FIG. 14 is a bottom view thereof.
